United States Patent Office.

THEODOR LEONHARD, OF PATERSON, NEW JERSEY.

Letters Patent No. 71,768, dated December 3, 1867.

IMPROVEMENT IN BLEACHING VEGETABLE OILS.

The Schedule referred to in these Letters Patent and making part of the same.

TO ALL WHOM IT MAY CONCERN:

Be it known that I, THEODOR LEONHARD, of Paterson, in the county of Passaic, and State of New Jersey, have invented a new and improved Method of Bleaching Vegetable Oils; and I do hereby declare that the following is a full, clear, and exact description thereof, which will enable those skilled in the art to make and use the same, reference being had to the accompanying drawings, forming part of this specification.

This invention relates to a new and improved method of treating linseed and other vegetable oils, in the process of bleaching and preparing the same for paint and other purposes; and the invention consists in providing for agitating the oil by a revolving shaft, with open or perforated wings attached thereto, within the vessel which contains the oil, while the same is being heated by a fire or by steam underneath, as will be herein-after described.

Figure 1 represents a top or plan view of the vessel with the agitator attached thereto.

Figure 2 is a vertical section of the same through the line *xx*.

Similar letters of reference indicate corresponding parts.

A represents an oblong vessel with a semicircular bottom, in which vessel the oil is placed. This semicircular vessel is supported by vertical sides and ends, *B*, as seen in fig. 2. It is placed upon a suitably-constructed arch, or other provision is made for applying heat to the same. In the centre of the vessel, extending longitudinally across it, there is a shaft, *C*, with wings, *D*, (more or less in number,) the sweep of which describes a circle corresponding (or nearly so) with the diameter of the circular bottom of the vessel. The wings *D* may be formed in any convenient manner to produce the desired effect. In this example of my invention the wings are composed of bars or rods, a portion of which are placed longitudinally with the vessel, and the balance are placed at right angles therewith. In the drawing, two wings are shown with the bars in the latter position. Wings formed of perforated plates or of wire cloth would probably answer the same purpose. The shaft is marked *E*, and it extends through the end of the vessel, so that a pulley or crank may be attached thereto. *F* represents a pulley on the end of the shaft, to which power may be applied for revolving the agitator. *G* is a bevelled edge or lip around the vessel, as seen in the drawing.

It is well known that vegetable oils are bleached by being exposed to the rays of light in glass vessels, and this method has hitherto been resorted to for that purpose; but the action of the light upon the quiescent oil at the temperature of the atmosphere does not produce the desired effect. I have discovered that by producing a constant and uniform agitation in the oil while the same is subjected to a moderate heat has the desired effect, and that linseed oil designed for paint may, by this treatment, be rendered fit for use in inside painting, by mixing it with a drier of my own composition, and which can be added while the oil is in a cold state, at any time, without coloring or staining it in the least, and without scorching or browning the oil, as is usually done by the ordinary process of boiling.

Having thus described my invention, I claim as new, and desire to secure by Letters Patent—

The vessel *A*, containing a revolving shaft, *E*, with wings *D*, or their equivalents, substantially as described, for the purpose of bleaching and preparing vegetable oils, as set forth,

THEODOR LEONHARD.
